CLAIM

The ornamental design for a seat cushion for bicycle, as shown and described.

DESCRIPTION

FIG. 1 a front elevational view of a seat cushion for bicycle showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof; and,

FIG. 8 is a perspective view thereof in position of use.

The broken lines showing a rider and portions of a bicycle illustrate environment and structure that form no part of the claimed design.
